CLAIM

The ornamental design for a multiple ball caddie, as
shown and described.

DESCRIPTION

FIG. 1 is a right rear perspective view of a multiple ball
caddie showing our new design;

FIG. 2 is a left side elevational view thereof;

FIG. 3 is a rear elevational view thereof;

FIG. 4 is a top plan view thereof;

FIG. 5 is a bottom plan view thereof;

FIG. 6 is a right rear perspective view of a modified
form of our new design of FIGS. 1-5;

FIG. 7 is a left side elevational view thereof;

FIG. 8 is a rear elevational view thereof;

FIG. 9 is a top plan view thereof;

FIG. 10 is a bottom plan view thereof.
